J. F. ZINK.

GUN RACK.

APPLICATION FILED FEB. 17, 1919.

1,302,267.

Patented Apr. 29, 1919.

UNITED STATES PATENT OFFICE.

JOHN F. ZINK, OF ALLEGANY, NEW YORK.

GUN-RACK.

1,302,267.

Specification of Letters Patent. Patented Apr. 29, 1919.

Application filed February 17, 1919. Serial No. 277,546.

To all whom it may concern:

Be it known that I, JOHN F. ZINK, a citizen of the United States, residing at Allegany, in the county of Cattaraugus and State 5 of New York, have invented certain new and useful Improvements in Gun-Racks, of which the following is a specification.

This invention has for its object to provide an improved and portable gun rack 10 equipped with a flanged retaining plate constituting a guard preventing accidental displacement of the guns mounted in the rack and operable by a foot lever of such design as to afford sufficient leverage to lift the 15 plate to inoperative position against considerable resistance and thus afford a convenient and effective means for quickly rendering the guns accessible.

Another object is the provision of means 20 associated with the retaining plate to positively lock the latter against movement and prevent removal of the guns.

With the above and other objects in view as will appear as the description proceeds, 25 the invention comprises the novel features of construction, combination and arrangement of elements which will be more fully described in the following specification and then set forth with particularity in the 30 claims appended hereto.

In the drawings:—

Figure 1 represents a front elevation of the improved gun rack,

Fig. 2 represents a similar view partly in 35 section,

Fig. 3 represents a transverse sectional view in the plane of the pivotal connection between the foot lever and actuating rods for the retaining plate,

Fig. 4 represents an enlarged detail sectional view through the upper portion of the 40 rack illustrating the retaining plate in detail, and

Fig. 5 represents a detail sectional view 45 of the plane of line 5—5 of Fig. 4.

Referring to the drawings in detail, wherein in similar reference numerals designate corresponding parts throughout the several views, the numeral 5 indicates a portable 50 base or supporting plate preferably of circular formation and provided with a series of radially disposed recesses 6 arranged in a circular series of such size and shape as to accommodate the butts of guns 7. For convenience, when transporting the gun rack,

the plate 5 is preferably mounted upon casters 8.

A braced standard 9 is secured centrally of the plate 5 and extends vertically therefrom and constitutes a support for the hook 60 plate 10 which is provided with a series of peripheral recesses to accommodate the barrels of the guns 7 and is rigidly secured against longitudinal movement upon the standard 9.

Guide rods 11 provided with angular lower terminals 12 are rigidly secured on top of the holder plate 10 and adjustably support a retaining plate 13 which is formed with a central aperture receiving the guide rods 11. 70 The upper terminals of the rods 11 are directed outwardly in opposite directions as indicated at 14 to prevent accidental removal of the retaining plate 13 and the latter is provided with a depending flange 15 which, 75 when the retaining plate is in its lowermost position, overlies the holder plate 10 and the barrels of the guns 7 to prevent unauthorized removal of the latter.

A foot lever 16 is pivotally secured at 17 in a bracket 18 attached adjacent the lower end of the standard 9 and is so arranged as to project between the guns mounted in the recesses 6 into such position as to be conveniently engaged by the foot. The inner 80 terminal of the lever extends into a substantially T-shaped opening 19 formed in the lower portion of the standard and a pin 20 is secured to the lever within one portion of the opening. Connecting rods 21 are attached at their lower ends to the pin 20, extend upwardly therefrom through the plates 10 and 13 and are provided with angular upper terminals 22 rigidly secured by 85 screws or any other suitable fastening means 90 to the retaining plate 13 whereby the movement of the lever 16 is imparted thereto. The extreme ends of the rods 21 are extended in contact with the opposed side faces of the rods 11 and are apertured as indicated at 24. In the alternate positions of the retaining plate 13 the apertures 24 register with spaced apertures 25 and 26 formed in the guide rods 11 and the shackle of a 95 pad lock 27 is designed for reception in the alined apertures in the connecting rods and brace rods to rigidly maintain the retaining plate in desired position.

When it is desired to provide free access to the guns mounted in the rack, the foot 110

lever 16 is actuated so as to elevate the retaining plate 13 and expose the barrels of the guns permitting convenient withdrawal of the latter from the rack. If preferred, the 5 retaining plate may be locked in elevated position by engaging the shackle of the pad lock 27 through the alined apertures 24 and 25. However, should it be desired to prevent the removal of the guns by unauthorized 10 persons, the retaining plate 13 is lowered to such position that the flange 15 overlies the barrels of the guns 7 preventing removal of the latter from the rack and the plate is locked in operative position by passing the 15 shackle of the pad lock through the alined apertures 24 and 26 and subsequently locking the pad lock.

What I claim is:

1. A gun rack including a recessed base 20 plate, a recessed holder plate arranged thereover, a retaining plate provided with a depending flange adapted to overlie the recessed holder plate and prevent unauthorized removal of guns from the rack, a foot lever, 25 and means connecting the foot lever with the retaining plate for manually operating the latter.

2. A gun rack including a recessed base

plate, a recessed holder plate arranged thereover, a standard mounted upon the base plate 30 and supporting the holder plate, a retaining plate movably supported upon the standard, a depending flange carried by the retaining plate adapted to overlie the holder plate and prevent unauthorized removal of guns from 35 the rack, a pivoted foot lever connected with the retainer plate for actuating the latter, and means for locking the retaining plate in adjusted position.

3. A gun rack including a base plate, a 40 standard mounted thereon, a recessed holder plate mounted upon the standard, guide rods mounted upon the holder plate, a retaining plate slidably supported upon the rods, a foot lever pivotally supported upon the 45 standard having angular upper terminals secured to the retaining plate, the side walls and connecting walls having apertures therein adapted to be moved into registration, and means engageable with said apertures for 50 locking the retaining plate in various adjusted positions.

In testimony whereof, I affix my signature hereto.

JOHN F. ZINK.
